UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MASSACHUSETTS.

WELT-BEATING MACHINE.

1,382,443.

Specification of Letters Patent. Patented June 21, 1921.

Application filed July 15, 1919. Serial No. 311,038.

To all whom it may concern:

Be it known that I, AUGUST R. SCHOENKY, a citizen of the United States, residing at Somerville, in the county of Middlesex and 5 State of Massachusetts, have invented certain new and useful Improvements in Welt-Beating Machines, of which the following is a specification, reference being had therein to the accompanying drawing.

10 This invention is a novel welt beating machine, by which I refer to a machine for beating or analogously reshaping the shoe welt strip attached to a shoe for the purpose of flattening it out preparatory to succeeding operations, such as the attachment of the outsole.

Heretofore known welt beating machines have proved very inefficient in the proper reshaping of the welt strip on the more difficult shapes of shoes, and the main object of the present invention is to overcome the difficulties heretofore encountered, and to afford a machine in which the welt may be expeditiously, efficiently, and non-injuriously flattened or reshaped. Other and more particular objects and advantages of the present improvement will appear in the hereinafter following description of one form or embodiment of the invention, or 30 will be apparent to those skilled in the art. To the attainment of the objects and advantages referred to, the present invention consists in the novel machine, mechanisms, devices, combinations and arrangements 35 herein illustrated, and described.

In the accompanying drawings, Figure 1 is a side elevation, partly in central section, of a welt beating machine embodying the present invention.

40 Fig. 2 is a top plan view of the same.

Fig. 3 is a right elevation of the hammer or beating tool.

Fig. 4 is a bottom view of the same.

45 Fig. 5 is a top view of certain interior parts in the head of the machine.

Fig. 6 is a section taken on the plane 6—6 of Fig. 1.

Fig. 7 is a bottom view or diagram showing the relation of the beating tool hereof 50 to the shoe during the operation of the present invention, the upper being designated U and the welt W.

The machine frame 10 has an extension 11 forming the seat for the removable an-

vil block 12, having its operative or machined surface 13 preferably horizontal. A slight recess 14 is shown at the inoperative side of the anvil for a purpose which will be explained.

Above the anvil is the beater or hammer 16, which has the usual down and up movements toward and from the anvil. The under surface of this tool at one side, and preferably radially arranged, has an elevation, rib or ridge 17, adapted at certain times, as 65 will be explained, to partake of the welt reshaping or flattening action.

The up and down movements of the beating tool 16 are effected by a vibrating arm 18, fulcrumed at 19, and having at its free 70 end a head 20, carrying the beating tool. For convenience, the upper portion 21 of the head and arm may be removable, giving access to the interior parts for assembling, cleaning, etc.

The operating shaft 22 is shown as provided with the usual fast and loose belt pulleys, and at a point beneath the arm 18 carries an eccentric 23. The eccentric strap 24 has its web or shank 25 extending upwardly 80 into pivotal connection with the vibrating arm 18. By this the arm, and therefore the beating tool, are given a rapid up and down vibration of small amplitude, so as to deliver repeated blows flatwise upon the outstanding welt material, as indicated in Fig. 1.

The beater tool 16 has its shank 26 extending up through the head to an exterior point, where a pair of lock nuts 27 are applied to it to limit or determine the normal position of the tool in the head. A leather washer 28 is placed beneath the lock nuts to minimize wear and shock. It is desired to apply the momentum of the tool 16 and 95 its shank to the work of reshaping the welt, but not the momentum of the head or arm of the machine, and consequently the tool and shank are rendered vertically slidable in the head, being held normally in the relative position shown by a spring 29, which yields, thus limiting the beating force, as stated, to that provided by the momentum or energy of the tool 16 and its shank 26. With the yield of the spring there will be a 105 slight separation between the lock nuts 27 and the head 20, the washer 28 taking up the shock on restoration of position.

The operating principle of the present invention is to afford a differential beating or reshaping action. With ordinary welt beaters the material is simply struck flatwise between the anvil and the hammer, and this is found to be incapable of satisfactorily flattening the welt, especially around the sharper turns of a pointed shoe. Broadly, the present invention operates so as to swage or spread the material of the welt to a greater degree at one edge, namely, the outer edge, than at the other or inner edge. This might be performed in different ways, for example, by a slight inclining of the anvil or hammer, but I prefer a differential spreading action which may be employed at will and set aside at will, so that the easier parts of the work may be performed in the usual manner by a simple, flat hammering action.

To this end I apply or form on one or the other of the two members, preferably the hammer member, a slight elevation, projection, rib or ridge positioned or capable of being positioned, so as to give an accentuated or increased swaging or spreading action along the outer edge of the welt. This may take the form of a radially arranged rib or elevation 17, tapered or graduated in degree or height, as indicated in Figs. 1, 3, 4 and 7. Fig. 7 shows the rib 17 in operative relation to the shoe and welt, and it will there be seen that the thicker or higher portion of the rib is applied to the outer edge or periphery of the welt. By this arrangement during the spreading or beating action, the periphery of the material is squeezed and swaged or spread to a greater degree than the inner part of the welt, thus materially lengthening the periphery and giving the differential spreading action before mentioned, so as to satisfactorily enable the welt to be properly flattened without resorting to the slashing or slitting, which has sometimes been adopted heretofore to a similar purpose.

Ordinarily the differential spreading action may not be required, and I have rendered the beating tool 16 circularly adjustable, so that at will the tapered rib 17 may be brought to the inoperative position shown in Fig. 1, where it may be accommodated within the recess 14 of the anvil, when not in action, or the operative position shown in Fig. 7.

In order to rotarily adjust the beater 16, a bevel gear 30 is fitted to a squared portion of the shank 26. This freely permits the yielding movement mentioned, while the gear is able to rotate the tool between its different operative positions. The bevel gear 30 is engaged by the bevel gear 31, mounted at the upper end of a shaft 32, mounted within the machine arm 18. In the present embodiment I propose only two adjusted posi-

tions of the welt beating tool 16, and to secure either of these positions a stop pin 33 is shown, mounted on the hub of the bevel gear 30 and engaging in a semicircular slot 34 in the machine head 20, as indicated in Fig. 5. When the pin is in the position shown, the differential surface or rib 16 of the beater is inoperative, as in Fig. 1, whereas, when the beater is rotated so that the pin 33 passes to the other extremity of the slot 34, the rib 17 will be brought to operative position, as indicated in Fig. 7.

I prefer to employ a spring 35, normally holding the shaft 32 and the beater tool in the position shown in Fig. 1. This spring in its lower end is held in the shaft 32, and its upper end engages in a socket piece 36, surrounding the shaft 32 and having peripheral teeth 37, as shown in Fig. 6, engaged by a worm 38, exteriorly accessible for rotating the stop piece and tightening the spring to any desired degree. The shaft 32 at its lower end has a bevel gear 39, engaging a bevel gear 40, mounted loosely on the axle or stud 19 on which the arm is fulcrumed. Secured around the hub of the bevel gear 40 is a pedal chain 41, presumed to be connected to a convenient pedal.

The operator holds the inverted shoe, as shown in Fig. 1, and guides it advancingly while the welt travels between the hammer and anvil, and is beaten into flat condition by a rapid succession of repeated blows. When the operator comes to a difficult part of the shoe, where the welt periphery is required to be spread more than in ordinary parts, he has simply to depress the pedal chain 41, thus giving a half turn to the hammer, without stopping the operation of the machine, and bringing the differential spreading means into operative position, as in Fig. 7. During the continued action, while the pedal is down, the welt periphery is swaged or spread to as great an extent as desired, depending on the rate at which the shoe is advanced, the operator watching the progress and carrying the flattening action progressively, either with or without the use of the invention, around the shoe, until the entire welt has been flattened.

It will thus be seen that I have thus described a welt beating or reshaping machine embodying the principles and attaining the objects of the present invention. Since many matters of design, combination, arrangement and detail may be variously modified without departing from the underlying principles, no limitation to such features is intended except as set forth in the appended claims.

What is claimed is:

1. A welt beating machine comprising an anvil, a beater vibratable above the anvil, a vibratable arm carrying the beater at its

free or head end, said beater having beating surfaces of different character, and connections comprising a longitudinal shaft mounted on the arm for transmitting rotation to 5 adjust the rotary position of the beater.

2. A welt beating machine comprising an anvil, a beater vibratable above the anvil, a vibratable arm carrying the beater at its free or head end, said beater having beating 10 surfaces of different character, and having its shank mounted both slidably and rotatably in the carrier head, a shaft extending longitudinally of said arm and bevel-gearred

to said shank to rotate it, and connections at the pivot of said arm for rotating said shaft. 15

3. A welt beating machine comprising an anvil, a beater vibratable above the anvil, a vibratable arm carrying the beater, means for vibrating the arm, and means for adjustably rotating said beater, the beater having a circular flat face interrupted by a single tapered rib extending from its center to periphery. 20

In testimony whereof, I have affixed my signature hereto.

AUGUST R. SCHOENKY.

It is hereby certified that the State of incorporation of the assignee in Letters Patent No. 1,382,443, granted June 21, 1921, upon the application of August R. Schoenky, of Somerville, Massachusetts, for an improvement in "Welt-Beating Machines," was erroneously given as "Massachusetts," whereas said State should have been given as *Maine*, as shown by the record of assignments in this office; and that the said Letters Patent should be read with this correction therein that the same may conform to the record of the case in the Patent Office.

Signed and sealed this 2d day of August, A. D., 1921.

[SEAL.]

KARL FENNING,

Acting Commissioner of Patents.
